ELBERON D. SMITH, OF BROOKLYN, NEW YORK, ASSIGNOR TO AMERICAN MACHINE & FOUNDRY COMPANY, OF NEW YORK, N. Y., A CORPORATION OF NEW JERSEY.

DRIVING MECHANISM FOR CIGARETTE MACHINES.

1,425,801.

Specification of Letters Patent. Patented Aug. 15, 1922.

Application filed October 15, 1919. Serial No. 330,708.

To all whom it may concern:

Be it known that I, ELBERON D. SMITH, a citizen of the United States, residing at Brooklyn, county of Kings and State of New York, have invented a new and useful Improvement in Driving Mechanism for Cigarette Machines, of which the following is a specification.

This invention relates to an improvement 10 in driving mechanism for cigarette machines.

For many years it has been common practice in the manufacture of cigarettes to employ a cigarette forming mechanism or cigarette machine proper operating at constant speed, together with an automatic feed mechanism therefor. It is well known in the art that in preparing tobacco for cigarette manufacture succeeding lots are not 20 always in the same order or condition, and that whatever the order or condition when the tobacco is prepared its condition is subject to change before manufacture into cigarettes, the change being due to changes in 25 atmospheric conditions or carelessness in handling the tobacco. It is also well known that when there is any change in the condition of the tobacco in a feed mechanism, there is a corresponding change in the rate 30 of tobacco feed because the action of the unchanging parts of the feed mechanism upon the tobacco differs with its condition. Such feed mechanisms therefore have always been equipped with a variable speed mechanism 35 by means of which the rate of feed could be changed when a change occurred in the condition of the tobacco. These automatic feed mechanisms were so constructed that the tobacco shreds were disentangled from a 40 mass in a supply hopper and showered upon a slowly moving forwarding belt, the result being that a sheet of tobacco was formed on the belt, this sheet consisting of loose shreds individually disentangled from the 45 mass in the hopper. The forwarding belt slowly delivered the sheet to a picker mechanism which acted thereupon and delivered the shreds in a shower to the cigarette machine proper. The quantity of tobacco on 50 this forwarding belt was sufficient for about a thousand cigarettes, and at the usual speed at which these machines were operated it took about three minutes for a shred to travel from the disentangling mechanism 55 along the forwarding belt to the picker mechanism which threw it down to the cigarette machine proper. In running his machine the operator usually discovers that a change has occurred in the condition of the tobacco by a change in the density of the 60 cigarettes made; that is to say, he discovers that they are running too hard or too soft, as the case may be. Heretofore when this happened, he could not change the speed of the cigarette forming mechanism for that 65 was constant, but he could and did operate the variable speed device of the automatic feed mechanism to increase or decrease its speed of operation. A prompt adjustment of the speed of the feed mechanism to suit 70 the new conditions could not result in immediately correcting the error in the cigarette forming mechanism because tobacco enough for a thousand cigarettes fed at the old rate had to be run out of the feed mechanism into 75 the cigarette forming mechanism before the proper quantity of tobacco could reach the latter. Thus, after an error of feed had been discovered and the proper steps taken to correct that error, there was always a loss 80 of about a thousand cigarettes unfit for the market before the error was really corrected. Such errors commonly occurred several times a day with each machine, and where a large number of machines was used the 85 loss was a substantial one. It has been discovered after many years of use that the old system of driving cigarette forming mechanisms and tobacco feed mechanisms therefor is wrong, and the main purpose of 90 the present invention is the production of a driving mechanism for cigarette machines which eliminates the losses above described. The invention consists in certain combinations and constructions which will be herein- 95 after fully described and then specifically pointed out in the claims hereunto appended.

In the accompanying drawings, which form a part of this specification and in which like characters of reference indicate the same or like parts, Fig. 1 is a side elevation partly in section of a device constructed in accordance with the invention, and Fig. 2 is a plan view partly broken away of the structure 105 shown in Fig. 1.

Referring to the drawings, 3 more or less diagrammatically indicates a cigarette forming mechanism of the well known "Standard" type, while 4 more or less diagram- 110

matically indicates an automatic feed mechanism of the well known Bonsack type. The particular construction of the two mechanisms lies wholly outside the present invention and a detailed description thereof is unnecessary to a full understanding of the present invention and is therefore omitted in the interest of brevity and clearness. It may be here remarked, however, that the feed mechanism includes a feed drum 5, a filling drum 6, a disentangling roll 7, a forwarding belt 8, and a picker roll 9, all of the usual construction and operation.

As above indicated, the cigarette forming mechanism and tobacco feed mechanisms differ from those well known in the art only in so far as the driving mechanism is concerned. In the present invention, the tobacco feed mechanism is operated at constant speed, while the speed of the cigarette forming mechanism may be varied. With this end in view, the feed mechanism is provided with a main power shaft 10 provided with a fast and loose pulley of ordinary construction, over which runs a driving belt 11 deriving its motion from a suitable constant speed line shaft. The shaft 10 also carries a conical pulley 12. Supported in brackets 13-14 bolted to the side of the cigarette forming mechanism is a power shaft for that mechanism marked 15. This power shaft carries a reversely disposed conical pulley 16. Running over the pulleys 12 and 16 is a belt 17 and this belt is moved along the pulleys 12 and 16 by means of belt shifting forks 18 constructed and operated in the usual manner.

By means of the mechanism just described, the tobacco feed mechanism is driven at constant speed and the cigarette forming mechanism is driven by means of the belt 17 connecting the two mechanisms, and the speed of the said belt can be varied at will. It is of course to be understood that the same changes in the condition of the tobacco will occur in the structure shown as in the old ones and that the sheet of tobacco on the forwarding belt will not always be of the same density although the feed mechanism runs at constant speed. It is well known that the time consumed by any shred of tobacco in traveling from the picker roll 9 down through the guiding hopper to the cigarette forming mechanism is but a small fraction of a second. When an operator of a cigarette machine equipped with the present invention discovers that the ma-

chine is making cigarettes too soft or too hard he at once operates the belt shifting device to decrease or increase the speed of the cigarette forming mechanism, including the rod forming tape which passes under the guiding hopper below the picker roll 9, and any particular point of the tape is therefore under the guiding hopper for a corresponding longer or shorter time than it was before. It follows that when the speed of the tape is decreased, more tobacco will be showered upon it as it passes under the guiding hopper; and when its speed is increased, less tobacco will be showered upon it and of course more tobacco showered upon the tape in a given time results in harder cigarettes, while less tobacco results in softer cigarettes. From the above it will be readily recognized that any error in the tobacco feed can be quickly compensated by varying the rate of speed of the cigarette forming mechanism and without the excessive loss in defective cigarettes heretofore encountered. Changes and variations may be made in the mechanism by means of which the invention is carried into effect. The invention therefore is not to be restricted to the precise details of the particular structure shown and described.

What is claimed is:

1. The combination with a cigarette forming mechanism, of a tobacco feed mechanism, therefor, means for operating said feed mechanism at constant speed, and means for driving and varying the speed of said cigarette forming mechanism.

2. The combination with a cigarette forming mechanism, of a tobacco feed mechanism, therefor, means for operating said feed mechanism at constant speed, and a variable speed device connecting said feed mechanism and said cigarette forming mechanism and driving the latter.

3. The combination with a cigarette forming mechanism, of a tobacco feed mechanism, therefor, means for operating said feed mechanism at constant speed, and a variable speed device connecting said feed mechanism and said cigarette forming mechanism and driving the latter, said device including a connecting belt, a belt shifter, and a pair of reversely disposed conical pulleys one carried by each mechanism.

In testimony whereof, I have signed my name to this specification.

ELBERON D. SMITH.
